GRILLWORK ARCHITECTURAL PANEL OR SIMILAR ARTICLE

Frank B. Miller, 1842 Ransom Road, Glendale, Calif.

Filed Oct. 15, 1959, Ser. No. 57,950

Term of patent 14 years

(Cl. D54—2)

The figure is a perspective view of a grillwork architectural panel or similar article showing my new design.

The dominant features of my new design reside in the portions shown in full lines.

I claim:

The ornamental design for a grill-work architectural panel or similar article, substantially as shown and described.
